UNITED STATES PATENT OFFICE.

J. HARPER SMITH, OF RARITAN, NEW JERSEY.

CLOTH-FINISHING MACHINE.

SPECIFICATION forming part of Letters Patent No. 249,859, dated November 22, 1881.

Application filed April 29, 1881. (No model.)

To all whom it may concern:

Be it known that I, J. HARPER SMITH, a citizen of the United States, residing at Raritan, in the county of Somerset and State of New Jersey, have invented certain new and useful Improvements in Cloth-Finishing Machines, of which the following is a specification.

This invention relates to that class of machines for cutting figures or designs upon cloth in which a relief-pattern upon a revolving cloth-supporting roller projects the surface of the cloth to meet the cutters. Its object is to produce upon the cloth clearly-cut, accurate, and uniform designs by projecting into the path of revolving cutters only a surface of the cloth precisely corresponding to the pattern, and by feeding the cloth over the pattern-roller at an unvarying speed, and to enable the cutting of closed designs composed of both transverse and longitudinal or diagonal lines as accurately upon wide or double-width as upon narrow or single-width cloths.

In some machines of this class as heretofore constructed, so great a surface of the cloth has been brought into the near vicinity of the cutters, on account of the comparatively large diameter of the pattern-roller, that often portions of the nap contiguous to the pattern would be cut away, giving the design a ragged uneven appearance. In others the cloth has been bent over a very small roller of wood inclosing a metal core tapering from the center toward the ends; but this small roller did not obtain by this construction the required stiffness, although provided with a supporting-roll. I obviate this disadvantage by arranging over the supporting-roller a casing which also incloses a portion of the pattern-roller, sustains the sides thereof, and serves as a guard to prevent contact of the cloth with said supporting or bracing roller, and also to guide the cloth at the proper angles to and from the pattern-roller. The small pattern-roller and its bracing-roller have heretofore been directly supported only at their ends, and in a machine for cutting designs upon wide or double-width cloth these rollers are so long in proportion to their diameter that their middle portions are liable to yield laterally to a very light pressure, and also to become warped, so that the surface of the pattern-roller is not maintained in

the same position with respect to the cutter at all parts of its revolution, and therefore the design is cut at varying depths, and often portions of the surface of the cloth which should be cut away are left untouched. I remedy this defect by arranging under the bracing-roller, at short intervals of its length, a series of adjustable bearing-rollers, whereby it may be maintained with its axis in a true rectilinear position, so that its surface will evenly brace the pattern-roller throughout its length, and prevent its swaying at any point.

Another evil which has attended this class of machines has been the slipping of the cloth upon the pattern-roller, whereby the parts of the designs have become unevenly spaced, and this defect I overcome by so proportioning the size of the pattern-roller, its supporting-roller, and the cloth drawing or feeding roller and their intermediate gearing that the circumferential travel of all these rollers shall be precisely the same, and the connections positive between them, so that there is no possibility of the cloth being stretched or fulled at any point, or of its slipping upon either of said rollers.

In the accompanying drawings, Figure 1 is a vertical transverse section of a machine constructed according to my invention. Fig. 2 is a partial front view of the same with a portion of the frame in section, the guide or guard casing in this view being removed to show the central parts. Figs. 3 and 4 represent samples of cloth having designs cut by my machine. Fig. 5 is a side view of the machine with some of the gearing removed to show the bearings of shafts.

The letter A designates the pattern-roller, upon which are formed in relief the patterns for the designs which are to be cut in the surface of the cloth. This roller has its ends journaled in standards A', supported by a bed-plate, F, which is itself supported by a suitable frame-work, F'.

Immediately above the pattern-roller, and parallel therewith, is arranged the cutter-roller B, provided with spiral cutting-blades b, this roller being mounted in an adjustable frame, B', by which it may be moved toward or from the pattern-roller as desired. The lower end of said frame is hinged to the bed-plate F at

b^2 , and the other is connected with the sides F' of the frame by means of bolts f , made preferably with a round head, entering a corresponding recess in the sides F' to form ball-joints therewith. The upper end of said bolts pass through the upper arms of the frame B' and retain the latter rigidly, after being adjusted by means of nuts f' , placed upon the bolts f above and under said arms of the frame 10 that supports the shaft of the cutter. The projecting shaft of this revolving cutter is provided with a belt-pulley, b' .

Directly below the pattern-roller A , with its surface parallel and in contact therewith, is journaled in boxes, adjustable vertically by means of washers or otherwise, the bracing or supporting roller C , below which are arranged, in pairs, the bearing-rollers D , which brace and maintain the roller C in its true position. 15 These bearing-rollers are journaled in blocks E , which rest upon the tips of adjusting-screws E' , which are tapped through the bed-plate F . The blocks E can also be adjusted laterally by the side screws, E^2 . The pairs of 20 bearing-rollers are arranged at short intervals of the length of the roller C , so as to perfectly control the same as to its position.

The letter J indicates a casing formed in two parts, adjustably secured by means of bolts 30 J' , passing through slots in the bottom flange thereof to the bed-plate F , and inclosing the roller C , its bearing-rollers, and the lower portion of the pattern-roller A , which revolves in a longitudinal slot formed in the top between 35 the two halves of said casing, its upper portion projecting above the casing in order to receive the cloth. The upper portions of the wall of the casing J are curved outwardly and downwardly away from the pattern-roller, and 40 serve as guides upon which the cloth passes to and from said roller. This casing extends the entire length of the rollers between the standards A' .

The projecting end of the shaft of the pattern-45 roller has fixed upon it a small gear-wheel, L , which meshes with a large gear-wheel, O , upon the shaft of the supporting-roller C , and this shaft is also provided with a similar gear-wheel, O' , which meshes with a motion-transmitting 50 gear-wheel, G , mounted in a slot in the bed-plate and meshing with another transmitting-wheel, G' , journaled below the bed-plate on a stud, g , projecting inwardly from the frame F' . This wheel G' meshes with a larger gear-wheel, 55 H , upon the shaft of the drawing or cloth-feeding roller I , which is journaled in arms K , projecting forward from the frame below the level of the bed-plate. This drawing-roller I is provided with projecting points, which engage 60 with the cloth and move it forward in the direction indicated by the arrow 1. It will thus be understood that the pattern-roller and the cloth-feeding roller carrying gears upon the shafts thereof, and being constantly and uniformly rotated together by means of intermediate gears meshing, as shown in the drawings, 65 said gears being properly proportioned, the cir-

cumferential travel of said rollers will be at precisely the same speed.

The letter M denotes a ledger-blade, arranged 70 with its edge above and close to the pattern-roller to hold the nap of the cloth in position to be properly cut.

The letters N N' designate guide-rollers for the cloth, which, in Fig. 1, is indicated by the 75 letter P . The shaft of the drawing or feed roller is connected with the driving-shaft of the machine, and may receive motion from any suitable source. This driving-shaft is shown in Fig. 5 at R , its driving-pulley being R' . There is mounted upon said shaft adjoining to the driving-pulley R' a small pulley, R^2 , giving motion by means of a belt, r^2 , to a pulley, S , upon the shaft s , and this shaft carries a pinion, S' , that gears with a large cog-wheel, H' , upon one 80 end of the shaft of the cloth-feeding roller I , giving a slow motion to the latter. A rapid motion is given to the revolving cutter B from a large pulley, R^3 , on the driving-shaft R by means of a belt, r^3 , passing over guide-pulleys 85 t and around the pulley b' upon one end of the revolving cutter-shaft. The cloth being drawn from a reel or receiver (not shown) is passed over the pattern-roller, as shown, and engaged 90 with the points of the feed-roller. The tension upon the cloth is then so adjusted as to draw it tight enough upon the pattern-roller to cause the relief-pattern to project a corresponding surface of the cloth outwardly beyond the general surface of the same, and in a position to have its nap cut away by the action of the enter-blades b against the ledger-blade. 95

The pattern-roller, supported as above described, can be used in combination with a plain rotary cutter, a revolving cutter having 100 notched blades, a notched ledger-blade, or a plain ledger-blade.

Having now fully described my invention, I claim—

1. In a machine for cutting figures or designs on cloth, the combination, with the pattern-roller of small diameter and its bracing-roller, of the adjustable casing J , to support the sides of said pattern-roller and to guide the cloth steadily to and from said pattern-roller, substantially as described.

2. The combination, with the pattern-roller and its bracing-roller, of the frame F and bearing-rollers D , and adjustable blocks E thereof, whereby the axles of said pattern and bracing rollers may be maintained in true rectilinear position, substantially as described.

3. The combination, with the pattern-roller A , its bracing-roller C , adjustable casing, and the feed-roller I , of gears positively connecting 125 said rollers, substantially as described, whereby the circumferential travel of all of said rollers will be precisely at the same speed, for the purpose specified.

J. HARPER SMITH.
